UNITED STATES PATENT OFFICE.

CHARLES H. GROTH, OF ROCHESTER, PENNSYLVANIA.

CHAMFERING PLANE.

1,425,764.

Specification of Letters Patent. Patented Aug. 15, 1922.

Application filed January 14, 1922. Serial No. 529,181.

To all whom it may concern:

Be it known that I, CHARLES H. GROTH, residing at Rochester, in the county of Beaver and State of Pennsylvania, a citizen 5 of the United States, have invented or discovered certain new and useful Improvements in Chamfering Planes, of which improvements the following is a specification.

My invention relates to chamfering planes 10 and consists in improvements of structure which render the instrument more effective and easier to use.

Fig. I is a view of a chamfering plane 15 of my invention, viewed in plan from beneath; Fig. II is a view of the plane in side elevation; and Figs. III, IV, and V are views in vertical section on the planes indicated in Fig. II by the lines III—III, IV—IV, and V—V.

20 The plane is an instrument for chamfering the chime of a barrel, that is to say, cutting a bevel around the inner edges of the assembled staves. It consists essentially of a guiding plate 1, adapted when in service to extend horizontally and to overlie the ends of the assembled staves. From plate 1 extends downwardly a plane with convex sole, *a*, *b*, the curvature of which sole corresponds in general to the curvature of the 25 rim of the barrel. The bit of the plane is indicated at 3. It is set at proper angle to the nether surface of plate 1, as best shown in Figs. I and V, and its cutting edge is preferably raked or inclined rearwardly from lower edge to upper, as best 30 shown in Fig. II. The plate 1 is provided with the usual handles 4 and 5, and the ends of plate 1 are preferably upwardly rounded, as indicated at *c* and *d*. The direction in which the instrument swings to 35 effect cutting is indicated by arrows in Figs. I and II.

I direct attention to the minute shaping of the sole of the plane. As in all planes the 40 blade or bit divides the sole into two parts, anterior and posterior, and in chamfering planes these two parts of the sole are commonly formed as two blocks 6 and 7, carried both of them by plate 1. The anterior 45 block 6 is ordinarily adjustable in radial direction (relatively to the circle of the barrel edge), adapting the instrument to use in barrels of different size. The anterior block 6 in its shape and disposition does 50 not differ essentially from the corresponding block of chamfering planes now commonly

in use. As best shown in Fig. III, its bearing face is nearly perpendicular in extension from the nether surface of plate 1, indeed it is slightly inclined in opposite inclination to the face of the bevel ultimately cut (sufficiently indicated in Fig. III by the limiting line of the edge of bit 3). And in consequence as the instrument advances to its work, it is the heel of bit 3, that is to 60 say the upper and rear portion of its edge, which comes first into play, and as cutting progresses, more and more of the edge becomes effective.

It is in the shaping of the posterior sole 70 block 7 that my invention is found. Hitherto that block has been provided with an inclined face, intended to correspond in inclination with the bevel ultimately cut. And it does so correspond when the bevel 75 is completed. But before completion of the bevel this part of the sole of the plane as hitherto constructed makes bearing only along its upper portion, adjacent the nether surface of plate 1. I have discovered herein 80 a cause of insecurity; the instrument in service is prone to jump when a knot is struck, and the user is likely to have his knuckles abraded on the edges of the staves. My invention consists in shaping the face 85 of this posterior block to convex curvature vertically (cf. Figs. IV and V) and in so disposing the curve that in service the bearing of this posterior portion of the sole of the plane shall, as cutting begins and progresses, engage the work at a point remote 90 from the nether face of plate 1. In consequence of this, the chamfering plane of my invention is more secure and the user is less liable to injury of the kind mentioned. 95

Coordinated with this bellying of the sole of the plane is the drooping of the handle 5. This handle ordinarily extends in substantially the plane of plate 1. I cause it to droop, as clearly shown in Figs. II and 100 III, and in consequence a larger component of the muscular force of the cooper is applied to holding the instrument down to the work, and in resisting occasional tendencies to jump—as when the bit meets a knot or 105 other hard place in the wood.

A feature of convenience is found in making integral anterior block 6 and handle 5. Block 6 is, as has been said, adjustable, and, by uniting handle 5 with it, the block 110 is more readily manipulated in making adjustment. The securing bolt is indicated

at 8; adjustment by means of a slot for the passage of the bolt is too well known to require analytic illustration. Moreover, the feature in itself forms no part of my invention.

It remains to explain the anchoring of the bit of the plane. Ordinarily the blade is clamped beneath a nut threaded on a shank extending obliquely from block 7, the opposite clamping surface being the nether surface of plate 1. Instead, I form a bridge 9, upon block 7 on the side remote from the sole and made integral at one end with plate 1. Beneath this bridge the bit 3 has play; through the web of the bridge 9 a screw 10 is extensible and a clamping block 11 distributes the stress of the screw over the surface of the bit. This superior anchorage

is more readily adjustable and in service is surer than the old form alluded to.

20

I claim as my invention:

A chamfering plane comprising a guiding plate to engage the edge of the stave, a transversely convex bottomed sole block projecting from the nether surface of the plate, and a straight edged chamfering blade with an edge in contact with the guiding plate.

In testimony whereof I have hereunto set my hand.

CHARLES H. GROTH.
